UNITED STATES PATENT OFFICE

WILLEM VAN RIJSWIJK, OF BADEN, SWITZERLAND, ASSIGNOR TO AKTIENGESELLSCHAFT BROWN BOVERI & CIE, OF BADEN, SWITZERLAND, A JOINT-STOCK COMPANY OF SWITZERLAND

BLADE FOR ROTARY BLOWERS AND COMPRESSORS

Application filed August 22, 1927, Serial No. 214,597, and in Germany August 25, 1926.

This invention relates to blowers, compressors, pumps and the like, of the rotary type in which the fluid is impelled by centrifugal force imparted by revolving blades. It has to do particularly with the construction of blades for such machines of large size adapted for operation at high speeds, wherein the rotating parts are subjected to high stresses from centrifugal force and from reaction from the handled fluid.

The general object of the invention is the provision of a blade construction whereby the weight of the rotating parts will be materially reduced, so as to reduce the centrifugal stresses on the shroud discs and shaft, and a proper strength maintained in the blades and in their connections to the shroud discs to withstand the pressures of the handled fluids. The ultimate object attained thereby is the possibility of constructing the blowers in large sizes and operating them at increased speeds, without unduly increasing the weight of the shroud discs and the diameter and length of the shaft.

Another object is the provision of a construction whereby these results may be attained economically.

A further object is the provision of a construction having the attributes mentioned, in which the blades may be made of high tensile steel.

Other and further objects of the invention will be pointed out or indicated hereinafter or will appear to one skilled in the art upon an understanding of the invention or its employment in practice.

In the drawing forming a part of this specification, I illustrate one form in which the invention may be embodied, but it is to be understood that this is presented by way of example only, as the invention which it is my purpose to secure under the appended claims is not limited to this particular construction. In said drawing:

Fig. 1 is a perspective view, with a portion in section, of an impeller blade embodying the invention and

Fig. 2 is a fragmentary sectional view illustrating the assembly of the impeller blade with the shroud discs.

In the designing of blades for centrifugal compressors to work with high peripheral speeds, it is difficult to obtain the necessary strength in the blades, particularly when they are of considerable width, without subjecting the shroud discs, shaft, and the blade connections, to undesirably heavy centrifugal forces resulting from the weight of the blades. The blades must possess a high degree of strength and stiffness transversely in order to prevent their bending on longitudinal lines under the heavy pressures reacting from the operation of the blades on the handled fluid, and for the same reason, the connections of the blades to the shroud discs must be very strong.

By the present invention, which is in the nature of a specific improvement on constructions illustrated in United States patent to Meyer No. 1,600,690, one is able to obtain strength in the blades by the use of high tensile steel with liberal dimensions for jointing contact between the edges of the blades and the faces of the shroud discs and also in the connecting means, without involving a commensurate increase in the weight of the blades. The nature of the improvement is illustrated in the accompanying drawing. In this the reference numeral 10 designates an impeller blade, and 11 the shroud discs to which it is connected. The blade is formed in the desired shape and size and then drilled transversely to afford the lightening channels 12 which are separated by transverse septa 14 of the metal. In this fashion the total weight of the blade may be reduced in a very material proportion without materially reducing the strength or stiffness of the blade transversely. Hence the blade may be constructed in the first instance with a substantial thickness so as to afford liberal bearing area between its edges and the faces of the shroud discs. At its margins the blade is provided with the rivets 16 which may be formed integrally of the blade material, and in order that these rivets may be of liberal size, exceeding in diameter the width of the septa, the channels opposite the rivets may be terminated short of the blade edge to leave the portions of metal 15 as supports for the rivets.

100

In order that the rivets on the two edges of the blade may be arranged in opposite relationship, the channels 12 are drilled in diagonal directions, as illustrated.

5 It will, therefore, be seen that in the present improved construction the blade is provided with adjacent passages extending obliquely with respect to the longitudinal axis 17 of the blade, each of such passages being
10 open at one end and closed at the other end by the material of the blade, the closed ends of such passages being disposed at opposite edges of the blade. Such construction or arrangement permits of placement of the blade-
15 retaining elements or rivets 16 adjacent the closed ends of such passages, as shown, the rivets being in alignment in a direction transverse to the blade and disposed on the imaginary line 18 perpendicular to the longitudinal
20 axis 17. Such alignment of the retaining rivets 16 provides for economies in manufacture and for better distribution of the blade-retaining forces.

When the blades are mounted, the rivets
25 are inserted through holes in the shroud discs and riveted down to draw them closely against the edges of the blade. The blades thus form beam-like connections between the shroud discs which, because of the permissible
30 thickness of the blades, is very strong and stiff transversely. At the same time, because of the lightness of the blades, it is not necessary to make the shroud discs undesirably heavy in order to sustain the centrifugal
35 forces.

I claim:

In blading construction for rotary fluid machines, an elongated blade, said blade being provided with adjacent passages extending obliquely with respect to its longitudinal axis and each being open at one end and closed at the other end by the material of said blade, the closed ends of said passages being disposed at opposite edges of said blade, and
40 blade-retaining elements associated with said blade and disposed respectively adjacent the closed ends of said passages and substantially on an imaginary line perpendicular to the longitudinal axis of said blade.

45 50 In testimony whereof I have hereunto subscribed my name at Zurich, Switzerland, this 4th day of August, A. D. 1927.

WILLEM VAN RIJSWIJK.
